UNITED STATES PATENT OFFICE.

THOMAS ARTHUR WOOLEY AND HERBERT FOX, OF HAMILTON, CANADA.

SHOCKING-MACHINE.

SPECIFICATION forming part of Letters Patent No. 784,609, dated March 14, 1905.

Application filed July 10, 1903. Serial No. 164,946.

To all whom it may concern:

Be it known that we, THOMAS ARTHUR WOOLEY and HERBERT FOX, citizens of Canada, residing at Hamilton, in the county of 5 Wentworth and Province of Ontario, Canada, have invented new and useful Improvements in Shocking-Machines, of which the following is a specification.

Our invention relates to improvements in 10 shocking-machines in which a framework carried by a reaper and binder machine is provided with certain mechanism for placing the sheaves one at a time from the binder into a sheaf-receiver until a shock is formed and the 15 rear end or head part of the receiver adapted to be raised to discharge the shock.

The objects of our invention are first to 20 place the sheaves from the binder into a receiver and to discharge said sheaves when formed into a shock and stand the same on its 25 butt-end. We attain these objects by the mechanism illustrated in the accompanying drawings, in which—

Figure 1 is a rear end elevation of the shocking-machine attached to the discharging side of a binder-machine and shown in normal position. Fig. 2 is an elevation of the same as viewed from the binder-machine, the tumbling-rod or oblique driving-shaft being 30 moved in order that a part of the driving mechanism of the shocking-machine may not be obscured. Fig. 3 is an enlarged sectional elevation of the gearing for driving the horizontal rake-shaft and rake, the binding mechanism, and the discharging mechanism, as 35 shown in Fig. 2 of the drawings. Fig. 4 is a rear end elevation of a part of the framework and detail mechanism for releasing the spring-catch 36 to allow the discharge of a 40 shock. Fig. 5 is an elevation of detail mechanism for sheaf engagement to release the spring-catch 22 to allow the shaft 4 to revolve once and as viewed from the binder-machine.

Similar characters refer to similar parts 45 throughout the several views.

In the drawings, A represents the framework of a reaper and binder machine; B, the ground drive-wheel; C, the deck; D, a stationary bar above the deck, and E is one of two or three 50 revolving sheaf-discharging arms of the binder.

The rigid framework of the shocking-machine is indicated by F and is carried by the binder-machine. Angle-iron posts H (shown in Fig. 1 of the drawings) are secured to the 55 binder-frame A. The upper part of the posts are supported by stay-rods J, which connect the posts to convenient places of the binder-machine. Angle-iron brackets K connect with the lower part of the shocker-frame F 60 and to the posts H at K', and stay-rods M connect the bracket K and the posts H in such a manner that the shocker-frame shall be firmly connected to the binder-frame and travel with the binder. A proper number of brackets K 65 and brace-rods M and P may be used to accomplish the proper stay and support of the shocker.

It will be seen in Fig. 2 of the drawings the extent and form of the shocker-frame F, which 70 is in elevation, the upper part of which is inclined toward the sheaf-receiver. (Shown in Fig. 1 of the drawings.)

The binder end of the drive-shaft N receives 75 its revolving power from a suitable part of the binder. At the shocker end of the shaft N the universal coupling 2 forms a part of the shaft N, and on the shocker end of the coupling 2 is secured a bevel-wheel 3, which revolves with the shaft N and the coupling 2. 80

In Fig. 2 of the drawings is shown the horizontal rake-shaft 4, which extends the length 85 of the shocker and is supported by a sleeve 5, which extends through the bearing 6 of the frame F and a bearing 7 of said frame at the opposite end thereof. The sleeve 5 referred to is shown in Fig. 3 of the drawings. The rake sprocket-wheels 8 and 9 are secured to the opposite ends of the shaft 4 and revolve with said shaft. The sleeve 5 revolves inde- 90

pendently of the shaft 4, and secured to the sleeve 5 is a spur-wheel 10, which drives a similar spur-wheel 12, which revolves loosely on the knotter-shaft 13, which revolves in the horizontally-extended bearing 14, which supports the knotter-shaft 13 and forms a part of the shocker-frame F. Secured on the knotter-shaft 13 is a clutch-disk 15, which forms a part of the crank 16. The clutch-box part 17 of the clutch-disk 15 forms a part of the 100 wheel 12 and revolves with said wheel.

The disk 15 has a pivoted catch 18. At the

opposite end of the knotter-shaft 13 is a knotter 19 and knotter-disk 20. Secured on the rake-shaft 4 is a clutch-disk 21, to which is pivoted a catch 22, which engages with the 5 clutch-box part 23 of said disk 21. The spring-catch 22 of the disk 21 is held in position by the spring-bar 86 in bearings 87 of the knotter-shaft bearing 14. (Shown in Fig. 5 of the drawings.) The end of the bar 86 is 10 provided with a blade 88, secured thereto and near to the knotter 19. At the opposite end of the bar 86 is a stop 89, secured thereto, and which engages the catch 22 of the disk 21.

90 is a spiral tension-spring on the bar 86. 15 One end of the spring is secured to the bar and the other end of the spring is secured to the knotter-shaft bearing 14.

The clutch-box part 23 forms a part of the bevel-wheel 24 and bevel-wheel 25, which are 20 secured to the sleeve 5 and revolve with said sleeve. The bevel-wheel 24, together with the bevel-wheel 25, is driven by the bevel-wheel 3, which is revolved continuously by the drive-shaft N.

25 26 is an oblique shaft supported in the lower foot-bearing 27 of the bearing 6 of frame F and the upper bearing 28 of the bearing 29. The lower part of the shaft 26 is provided with a bevel-wheel 30, (shown in Fig. 2 of 30 the drawings,) which is secured to the shaft 26. The wheel 30 is revolved by the wheel 25, previously referred to. To the upper part of the shaft 26 is secured a bevel-pinion 31, which gears into and revolves the bevel-wheel 32, which revolves loosely on the crank-shaft 33 in bearings 29 and 34. The bearing 34 forms a part of the frame F. The clutch-disk 35 is secured on the crank-shaft 33, and a spring-catch 36 is pivotally connected to the 35 disk 35.

37 is the clutch-box part of the clutch-disk 35 and is a part of the wheel 32. A rock-frame 38 is loosely connected to the rear end of the rake-shaft 4, (shown in Figs. 2 and 3 45 of the drawings,) and a rock-arm or rock-frame 39 is loosely connected to the rake-shaft 4 at the opposite end thereof. The rock-frames 38 and 39 operate together and always at the same time and by the same means.

50 The upper part of the rock-frame 38 is formed as an elongated bearing to support a through-shaft 40, which is adapted to revolve loosely in said bearing of the frame 38. A sprocket-wheel 41 is secured to the rear end 55 of the shaft 40 and is revolved by the sprocket 8 by means of the sprocket-chain 42, which connects the sprockets 8 and 41. The sprocket 8 is secured to the rear end of the rake-shaft 4.

The bearing which forms the upper part of 60 the rock-arm 39 supports a shaft 43, which revolves therein, and to the forward end of the shaft a sprocket 44 is secured thereto. The sprocket 44 is revolved by the sprocket 9 by means of the sprocket-chain 45. The sprocket 65 et al referred to are all of one size and revolve

together by the same means and at the same time—that is, when the rake-shaft 4 revolves. The forward end of the shaft 40 of the rock-frame 38 has a crank 46 secured thereto, and the rear end of the shaft 43 of the rock-arm 70 39 has a crank 47 secured thereto. The cranks 46 and 47 are similar and revolve together. The ends of the sheaf-frame 48 are pivotally connected to the cranks 46 and 47, and when said cranks revolve the frame is brought toward the binder-machine, together with its arms or teeth 49, the upper part of which are secured to the frame 48. The teeth 49 take hold of the binder side of each sheaf in succession as the sheaf is discharged from the 80 binder upon the raised strips 50, which are secured to the table or deck part 51 of the shocker. The teeth 49 are located to operate between the strips 50 and over the table part 51 of the shocker immediately after each sheaf 85 is discharged from the binder.

52 is a stationary bar one end of which is secured to a stationary bar D of the binder, (shown in Fig. 1 of the drawings,) and the other end of the stationary bar 52 is secured to a 90 convenient part of the frame F of the shocker. 53 is a column (shown broken) secured to the bar 52 and extends a suitable distance above said bar 52. The connecting-rod 54 is pivotally connected to the upper end of the column 95 53 to allow said rod 54 to swing. An arm 55 is securely connected to the frame 48 and pivotally connected to the lower end of the rod 54. The part of the shocker indicated by 52, 53, 54, and 55 forms a link connection to the 100 frame 48 to retain said frame in proper and suitable and almost at varying vertical position when said frame 48 is brought toward the binder in order that the teeth 49 of said frame 48 may engage each sheaf as it 105 is consecutively discharged from the binder onto the strips 50 of the shocker. The needle-shaft 56 above the upper part of the frame F is suitably journaled in the bearing 57 of the frame F and extends into the bearing 58 at the other end of the shaft. Secured on the shaft 56 and in proximity to the said bearing 58 is the needle 59, which operates with its shaft 56. The bearing 58 is a part of the bearing 60, secured on the frame F and 115 which supports an extended round bar 61, held rigid in the bearing 60. (Shown in Fig. 1 of the drawings.) On the round bar 61 is a sleeve 62, which is adapted to swivel on said bar 61. The sleeve 62 is secured to the horizontal bar 64 by means of the flange 63 of said sleeve. The bar 64, together with the sleeve 62, is adapted to swivel on the stationary bar 61.

The arms 65 and 66, together with the inner sheeting 67 thereof, is the sheaf and shock receptacle. The upper end of the arms 65 and 66 are secured to the bar 64 and swivel together with said bar on the stationary bar 61. In the motion of the receptacle 67 the 130

rear arm 65 rises and the arm 66 lowers to discharge the shock.

On the horizontal bar 64 is a bracket 68, secured thereto, and the connecting-rod 69 is 5 pivotally connected to the bracket 68 and to the crank 70, which is secured on the lower end of the shaft 33 in bearing 34 of the frame F. The rear end of the needle-shaft 56 has an oscillating crank 71 secured thereto to rock 10 said shaft, and a connecting-rod 72 connects the crank 71 with the crank 16 of the knotter-shaft 13. The clutch-disk 15, which is secured on the knotter-shaft 13, has a pivoted catch 18, previously referred to. The lower 15 part of the spring-lever 73 engages with the catch 18 of the clutch-disk 15. The lever 73 is fulcrumed to the bracket 74 on the frame F. A cord or chain 73^a is attached to the upper part of the lever 73 and the other end of 20 the cord to the driver, that the cord may be pulled to release the catch 18 when the shock is formed.

A spiral spring 75 engages the bracket 74 and the lever 73 in such a manner that the 25 lower end of said lever shall engage the catch 18 of the clutch-disk 15 until the said catch is released from the lever 73.

The clutch-disk 15, together with its catch 18 and clutch-box 17, is of similar construction as the clutch-disk 21, with its catch 22 and box 23, on shaft 4 and the clutch-disk 35, with its catch 36 and box 37, on shaft 33 in the bearing 34 of frame F and for similar purposes—namely, that when each said catch 35 is released the clutch-box adjoining, together with its adjoining and connected wheel, revolves. A bracket 76 is rigidly connected to the frame F. To the bracket 76 one end of the connecting-rod 77 is pivotally connected, 40 and the other end of said rod is pivotally connected to an outer crank part 79 of the sprocket 41. (Shown in Fig. 1 of the drawings.) A similar bracket 80 is rigidly connected to the other end of the frame F, and the connecting-rod 81 is pivotally connected to said bracket 80, and the other end of the rod 81 is pivotally connected to an outer crank part 82 of the sprocket 44.

The rods 77 and 81 referred to are for the 50 same object and purpose—namely, to allow the rock-frame 38 and the rock-arm 39, previously referred to, to rock a certain distance toward the binder, together with the sprocket-wheels 41 and 44, and the sheaf-frame 48, with 55 its teeth 49, when said sprockets 41 and 44 are revolved.

83 is the shock-binding twine and extends from the needle 59 to the knotter 19.

The head part of a sheaf S is shown in broken 60 lines in Fig. 1 of the drawings and in position on the strips 50 when discharged from the binder. The lower part of the rake-teeth 49 and the crank 46 are also shown in broken lines. The teeth 49 at the binder side of the 65 sheaf are in position to engage the sheaf and

discharge the same into the receptacle 67. One sheaf is shown in broken lines in the receptacle 67. The broken circular line T around the sheaf S on the strips 50 shows the line of travel or progress of the lower end of the 70 teeth 49 previous to engaging each sheaf in succession and also the progress of or line of travel of the rake-teeth in broken line below the broken-line representation of a sheaf after discharging the sheaf into the receptacle 67. 75

The operation of the machine is as follows: The binder ground-wheel B revolves, as indicated by arrow, when the machine is at work. The tumbling - rod and drive - shaft N is revolved at the same time by means of binder- 80 machine mechanism, to which one end of the shaft N is connected. The bevel-wheel 3 of the coupling 2 of said shaft N is also revolved, as indicated by arrow. The wheel 3 gears into the bevel-wheel 24, and consequently 85 revolves the bevel-wheel 25 and the clutch-box 23, together with the sleeve 5, at the same time and loosely on the rake-shaft 4. The rake-shaft 4 is suitably journaled in the stationary frame F of the shocker, said frame being suitably connected to the side of a binder. At 90 this time the wheel 25 revolves the bevel-wheel 30. Consequently the shaft 26 and the pinion 31 on said shaft are revolved. The bevel-wheel 32 is revolved by the pinion 31 95 and loosely on the crank-shaft 33. The deck 51 of the shocker has a slot 91 to allow the blade 88 to operate. When a sheaf S is being discharged from the binder, the sheaf S engages with the blade 88, which protrudes 100 through the deck 51, and consequently rotates the bar 86, together with the stop 89, thereby releasing the catch 22 of the disk 21 to allow the shaft 4 to revolve once and operate the rake 49. The catch 18 of the knotter-shaft is 105 released when the shock is formed to allow the shock to be bound. The spring-catch 36 is held in position by the spring trip-bar 84, which is secured to the frame F and shown in Fig. 4 of the drawings. The spring trip-bar 110 84 has a lip 85 in contact with the catch 36, and the trip-bar 84 is so arranged that when the needle - crank 71 moves downward the crank 71 engages the trip-bar 84 to release the catch 36. Consequently the plate 35, the 115 coupling-box 37, the shaft 33, together with the crank 70, revolve once to discharge the shock. When the catch 22 is released, the rake-shaft is allowed to revolve once. Consequently the sprockets 8 and 9 on the shaft 120 4 are revolved one revolution. The sprockets 40 and 44 are also revolved one revolution by means of their chains 42 and 45, respectively. At this time the cranks 46 and 47 are revolved. The connecting-rods 77 and 81 allow 125 the sprockets 40 and 44 to be brought toward the binder-machine, together with the frame 38 and the rake-frame 48. When the frame 48 is being brought toward the binder, said frame is retained in almost perpendicular po- 130

sition by means of the link-motion, comprising the arm 55 and the rod 54. The first half-revolution of the cranks 46 and 47, referred to, allows the frame 48 to rise upward on its motion toward the binder, in order that the arms or teeth 49 of said frame 48 may rise over the sheaf which has been discharged from the binder and placed in proximity to the teeth 49 of the rake-frame 48. The teeth 49 at the second half-revolution of the cranks 46 and 47, together with the operation of the connecting-rods 77 and 81, allow the teeth 49 to engage the sheaf at the binder side thereof and carry the sheaf into the sheaf-receptacle 67. The operation of carrying the sheaf into the receptacle 67 is repeated until a sufficient number of sheaves is placed into the receptacle to form a shock. The first sheaf of the shock takes the twine 83 with it into the sheaf-receptacle 67 and rests on said twine. The sheaves which follow in succession push the first sheaf, together with the twine, so that when the number of sheaves are formed into a shock a sufficient length of twine is allowed to tie the shock. Immediately the shock is formed the spring-lever 73, which controls the knotter-shaft, is withdrawn from the catch 18. The catch then engages the clutch-box 17, thereby allowing the knotter-shaft 13 to revolve once by means of the spur-wheels 10 and 12, the spur-wheel 12 being a part of the clutch-box 17. At this time the crank 16 on the knotter-shaft 13 revolves once, and the crank 71 of the needle-shaft 56 is rocked by means of the connecting-rod 72, which connects the cranks 16 and 71, thereby allowing the needle 59 to engage the knotter 19 and tie the shock. Instantly the shock is tied the catch 36 of the clutch-disk 35 is released, thereby allowing the clutch-box 37, together with the crank-shaft 33 and the crank 70, to revolve once. The connecting-rod 69 connects the crank 70 with the bracket 68 on the horizontal bar 64 to lift upward the rear end of the receptacle 67 on its pivotal center 61 to stand the shock on its end. The forward end of the receptacle is sufficiently high to allow the receptacle to pass over the top of the shock. The crank 70 in its first half-revolution carries the receptacle 67 upward to discharging position, and the second half-revolution of said crank 70 brings the said receptacle to normal position to receive other sheaves, as set forth.

The broken circular line U in Fig. 2 of the drawings indicates the line of progress or travel of the forward lower part of the receptacle 67 toward the rear of the machine and upward when discharging the shock. The said lower part when brought upward to its limit is sufficiently high to pass over the head of the shock when the same is standing on the ground and the machine in motion.

What we claim as our invention, and desire to secure by Letters Patent, is—

65 1. The combination with a binder, of a shock-

ing-machine, comprising a frame connected to the frame of the binder at the discharge side thereof, a horizontal bearing secured to the lower part of the frame, a knotter-shaft adapted to revolve in the bearing, a 70 horizontal operating-shaft, a sleeve on the operating-shaft, a bearing for said sleeve, and means on said sleeve to revolve the knotter-shaft, substantially as set forth.

2. The combination with a binder, of a shocking-machine, comprising a frame connected to the discharge side of the binder, an operating-shaft journaled in the frame, a rock-frame journaled on the operating-shaft, a shaft journaled in the rock-frame, a sprocket on the 80 operating-shaft, a sprocket on one end of the rock-frame shaft revolved by the operating-shaft sprocket, a crank on the other end of the rock-frame shaft, and a rake operated by the crank, substantially as set forth. 85

3. In a shocking-machine, a frame, an operating-shaft suitably journaled in the frame, rock-frames journaled on the ends of the operating-shaft, shafts extending through said rock-frames, sprockets on said rock-frame 90 shafts and sprockets on the operating-shaft connected to the rock-frame sprockets, cranks, a floating rake-frame pivotally connected to the cranks, teeth on the rake-frame, and means for causing the rake-frame to float in 95 a predetermined path when operated by the cranks, substantially as set forth.

4. The combination with a binder, of a shocking-machine, comprising a frame, an operating-shaft journaled in the frame, rock-frames 100 journaled on the shaft and adapted for movement toward the binder, shafts loosely journaled in the rock-frames, cranks on the shafts, a rake-frame pivotally connected to said cranks, means to limit the rock-frames to a 105 predetermined oscillation, and means to revolve the crank-shafts, substantially as set forth.

5. The combination with a binder, of a shocking-machine, comprising a frame connected 110 to the discharge side of the binder, a deck on said frame, strips on the deck to receive the sheaves from the binder, a movable rake-frame having rake-teeth, said teeth adapted to operate between said strips, and means for 115 moving the rake-frame to cause the teeth to operate between the strips, substantially as set forth.

6. In a shocking-machine, a machine-frame, a bracket secured to the frame, a substantially 120 horizontal stationary bar rigidly secured to the bracket, a sleeve adapted to revolve on said horizontal bar, a second horizontal bar rigidly secured to the said revoluble sleeve, a sheaf-receptacle connected to said last-named horizontal bar and adapted to swing with it, and means for swinging the last-named horizontal bar and receptacle into an upright position to discharge the shock and for returning it to 125 sheaf-receiving position. 130

7. In a shocking-machine, a frame, a bearing on the frame, a sleeve journaled in the bearing, an operating-shaft extending loosely through said sleeve, bevel-gears connected to each other and secured to said sleeve, a clutch interposed between the gears and shaft and adapted to revolve said shaft, a drive-shaft having a gear meshing with one bevel-gear, a bundle or sheaf receptacle, and a gearing interposed between the other bevel-gear and the bundle or sheaf receptacle, substantially as set forth.

8. In a shocking-machine, a machine-frame, a rake-operating shaft, a rake, means for operating the rake from the said rake-operating shaft, a rotary sleeve on the said rake-operating shaft, bevel-wheels secured to said sleeve, a tilting sheaf-receptacle, a crank-shaft having operative connection with the sheaf-receptacle for tilting said sheaf-receptacle, gearing interposed between said crank-shaft and one of the bevel-wheels aforesaid, a drive-gear meshing with the other bevel-gear, a clutch on the rake-operating shaft co-operating with said last-named bevel-gear, whereby the rake-shaft is driven, a knotter-shaft, a knotter operated by said shaft, and gearing interposed between the sleeve and the knotter-shaft.

9. In a shocking-machine, the combination with a machine-frame, of rockers, crank-shafts journaled in said rockers and movable with the rockers, a rake carried by the cranks on said crank-shafts and operated thereby, means connecting the rake to a fixed support whereby the rake is anchored and made to move in an

orbit, means for rocking the rockers, and means for turning the crank-shafts carried by said rockers, whereby the rockers displace the rake as an entirety, and the crank-shafts cause said rake to operate.

10. In a shocking-machine, the combination with a tilting bundle or sheaf receptacle, of means for tilting said receptacle into a general upright position to discharge the sheaf therefrom, a substantially horizontal shocker-deck for initially receiving the sheaf, rockers, a rake carried by said rockers and adapted to convey the sheaf from the shocker-deck to the receptacle, means for operating the rake, and means for vibrating the rockers.

11. In a shocking-machine, the combination with a stationary machine-frame, of a bracket fixedly secured to said machine-frame, a shaft secured to said bracket and extending horizontally, a second bracket journaled on the shaft, a horizontal shaft or bar secured to the bracket last named and adapted to tilt therewith into a general upright position, hangers depending from the bar aforesaid, a sheaf-receptacle secured to said hangers, another bracket secured to the bar, a crank and pitman operatively connected to the bracket secured to the bar, and means for operating the crank and pitman to position the sheaf-receptacle in upright or horizontal position.

THOMAS ARTHUR WOOLEY.
